CHARLES E. DE LONG, OF SAN DIEGO, CALIFORNIA, ASSIGNOR TO SANGAMO ELECTRIC COMPANY, OF SPRINGFIELD, ILLINOIS, A CORPORATION OF ILLINOIS

ASTRONOMICAL TIME SWITCH

Application filed March 16, 1929. Serial No. 347,513.

The present invention relates to astronomical time switches, such as are employed to exercise a governing function over some controlled apparatus in predetermined time relation to sunset or sunrise, or both. For example, these switches may be utilized to control large electric display signs, signal apparatus and various other mechanisms in which it is desired that the operation be in timed relation to sunrise or sunset; i. e., in the case of an electric sign, that the sign be switched on at sunset or at a predetermined interval earlier or later than sunset, and be switched off at a definite hour in the morning or in predetermined timed relation to sunrise.

Considering first an installation wherein it is desired to have the device close a circuit approximately at sunset, or say twenty minutes earlier or later than sunset, it will be apparent that the actual time of operation of the switch will have to vary from day to day with reference to clock time to correct for the different hours of sunset in the different seasons of the year. The prior constructions of time switches which have been designed to have this mode of operation have been extremely complicated and very expensive, so much so that their cost is usually prohibitive except in large installations warranting their high cost. Moreover, these prior constructions have been subject to considerable error in effecting the automatic change of operation with seasonal variations in sunset or sunrise. It is one of the principal objects of the present invention to provide an astronomical time switch which is of comparatively simple construction, comparatively inexpensive in initial cost and maintenance, and which is much more accurate in effecting seasonal variations than the prior constructions with which I am familiar.

Another object of the invention is to provide improvements wherein one actuation of the switch, usually corresponding to the opening actuation thereof, can be made to occur at a definite fixed hour each morning, or wherein such actuation can be made to occur at sunrise or in predetermined timed relation thereto.

In this regard, it is a further object to provide improved means which can be quickly and easily adjusted for adjusting the time of operation of the switch either with reference to sunset or sunrise, or for adjusting the fixed time of opening of the switch irrespective of sunrise, where such latter mode of operation is desired.

Another object of the invention is to provide improved cut-out means capable of rendering the switch non-effective at certain time periods, when such is desired. For example, such cut-out means may be employed to make the switch non-effective on Sundays, when such is desirable, although this means may be employed for cutting out the operation on any other days.

Other objects and advantages of the invention will appear from the following description of the preferred embodiment thereof. In the accompanying drawings illustrating such embodiment—

Fig. 1 is a front view of the device with the cover swung back to illustrate the grouping of the different mechanisms in the enclosing housing;

Fig. 2 is a circuit diagram of the electrical connections between the different mechanisms, such mechanisms being shown in approximately the relation they occupy in the housing;

Fig. 3 is an elevational view of the astronomical or time changing mechanism showing its mounting on the clock unit;

Fig. 4 is a fragmentary side or edge view of the same, as viewed from the bottom of Fig. 3;

Fig. 5 is a transverse sectional view through such mechanism, taken approximately on the plane of the line 5—5 of Fig. 3;

Fig. 6 is a view similar to Fig. 3, but with the hour wheel removed to illustrate the month wheel;

Fig. 7 is a detail view of the shifting lever which swings the switch actuating parts in accordance with the movement of the season cam;

Fig. 8 is an elevational view of the mounting arm or lever which supports the switch actuating disc;

Fig. 9 is a side view of the same;

Fig. 10 is an inverted view of this assembly, as viewed from the rear side of Fig. 8;

Fig. 11 is an end view of such swinging arm and switch actuating disc;

Fig. 12 is a view of the reverse side of the month wheel, showing the season cam mounted thereon;

Fig. 13 is a detail sectional view showing the construction of the relay switch; and

Fig. 14 is an elevational view, somewhat diagrammatic, showing a modified embodiment adapted for varying the switch closing and opening operations in accordance with seasonal variations of sunset and sunrise.

The device is enclosed in a housing 17, the front of which is open to afford access to the mechanism for adjustment thereof. This open front is normally closed by a cover 18 which is hinged to the housing 17 and is preferably capable of being locked thereto. The interior of said housing is divided by two transverse partitions 19 into upper, intermediate and lower compartments. Mounted in the upper compartment is a clock unit 20 comprising any suitable time controlled mechanism such as a conventional time train and escapement mechanism driven by a manually wound clock spring or by an electric motor. Mounted in the intermediate compartment is a motor driven switch actuating mechanism 21 which is periodically actuated under the control of the clock unit 20 for actuating the main switch 22. Such main switch is mounted in the lower compartment of the housing. The present invention resides primarily in the time changing mechanism associated with the clock unit 20. The motor driven switch actuating mechanism 21 may be of any preferred construction, the same merely serving as a power source or relay for transmitting a relatively large operating energy to the main switch 22 under the comparatively delicate control of the clock unit 20. Similarly, the main switch 22 may be of any preferred construction, a toggle type of switch being shown in the disclosure. The energization of the switch actuating mechanism 21 is under the governing control of a pilot or relay switch 23 associated with the clock unit 20, and the invention pertains primarily to the time control of this relay switch.

Referring to Fig. 3, the minute hand arbor 24 extending outwardly from the clock movement is indicated at 24, such arbor making one complete revolution each hour. Suitably secured to this arbor, to rotate therewith, is a small spur gear 25 which meshes with a larger spur gear 26 rotating about a laterally disposed arbor 27. Secured to the gear 26 is a relatively small spur pinion 28 which transmits rotation to a larger spur gear 29. The gear 29 is joined to another gear 31 whereby both gears rotate as a unit, such pair

of gears being secured in axially spaced relation on a sleeve 32 which is mounted for free rotation on the arbor 24. The ratio of the gear reduction from the gear 25, which rotates once each hour, through the speed reducing gears 26 and 28 is such that the double gear unit 29-31 will complete one revolution every twelve hours, corresponding to the hour hand on the clock, if such were employed. The gear 29 is divided into twelve divisions, each indicated by the numerals 29' reading from "1" to "12", inclusive, and its companion gear 31 is similarly divided into twelve divisions, each indicated by the successive numerals 31' extending from "1" to "12", inclusive. Cooperating with the numeral indicia 29' is an index pointer 33 stationarily secured to the clock frame. The numeral indicia 31' on the companion gear 31 is not in registry with the numeral indicia 29', the numerals 31' being adapted to establish timing registration with corresponding hour numerals 34' on a wheel 34 which is driven by the gear 31.

The gear wheel 34 rotates about the axis of a spindle or arbor 35 projecting outwardly from the clock frame, and such wheel is relatively large, its ratio to the driving gear 31 being such that the wheel 34 will make one complete revolution every twenty-four hours. Each half of the wheel is separated into twelve divisions, represented by the numerals 34', each series of numerals corresponding to the twelve hours A. M. and the twelve hours P. M. of each day. The two series of numerals are separately designated by the A. M. and P. M. indicia as shown, and the Day and Night sections of the wheel are correspondingly indicated.

I shall hereinafter refer to the wheel 34 as the "hour of the day" or "hour" wheel in the series of time wheels to be later described. Such wheel comprises a hub 36, projecting from the upper and lower sides of the wheel, and mounted on such hub on the upper side of the wheel is a tripping finger 37, and mounted on said hub on the lower side of the wheel is a similar tripping finger 38. These fingers have split hub portions 37' and 38' (Fig. 5) engaging with a relatively tight frictional fit over the projecting portions of the wheel hub 36. Such mounting enables the two fingers to be adjusted to different angular points about the wheel, corresponding to different hours of the day or night when the main switch is to be opened and closed. The outer nose or tripping portion of each finger projects slightly beyond the periphery of the wheel 34, and the straight radial edge of this nose constitutes an index point which is adapted to be placed in registry with the desired hour numeral 34' or fractional part of the hour, corresponding to the time when the switch is to be actuated.

The under side of the wheel 34 has corre-

sponding hour indicia and A. M. and P. M. and Day and Night indications for indicating the angular setting of the lower tripping finger 38, such indicia being angularly displaced, however, from the numeral indicia 34' on the upper side of the wheel, owing to the fact that the lower finger 38 performs its tripping function at a different point in the rotation of the wheel than does the upper tripping finger 37, as will be hereinafter described. In cutting the teeth in the wheel 34, the tooth spaces are extended inwardly into the body of the gear in the form of shallow radial grooves 41 to indicate fractional parts of the hour between successive hour numerals 34', this being true on both sides of the gear.

The hub 36 of said gear is adapted to fit down over a small gear element 42 which is 20 rotatably mounted on the pivot or arbor 35, the gear 34 operating to drive the small gear 42 and thereby transmit rotation to another large gear wheel 43 disposed below the hour wheel 34. As shown in Fig. 5, the gear 42 is 25 formed with an outwardly or upwardly extending sleeve portion 44 having a reduced upper end upon which the hub 36 of the gear 34 seats, whereby the gear 34 is held in spaced relation to the gear 43. As shown in Fig. 3, 30 the upper end of said sleeve 44 is provided with a radially extending key 45 adapted to engage in a corresponding socket formed in the hub 36. The gear 34 can be readily lifted off the end of the sleeve 44 to permit adjustments in the assembly or setting of the mechanism.

To normally retain the gear on said sleeve, retaining means in the form of a wire 46 is extended from a post 47, around which one 40 end of the wire is coiled, and is adapted to be sprung into a transverse slot in the outer end of the pivot standard 35. When it is desired to adjust the timed angular relation of the lower tripping finger 38 or of the wheel 45 34, it is only necessary to spring the wire 46 out of the slotted end of the arbor 35 and to swing said wire to one side, whereupon the wheel can be lifted off the end of the sleeve 44 for effecting angular adjustment between 50 these parts, it being noted, however, that said wheel can only be replaced in one angular position with respect to the small gear 42, such being determined by the engagement of the key 45 in the keyway formed in the hub 36.

The gear wheel 43 is rotatably mounted on a fixed pivot standard 49 projecting outwardly from the clock frame, the ratio between such gear and the smaller gear 42 which drives it being such that the wheel 43 makes one complete revolution for every seven revolutions of the wheel 34, i. e., one complete revolution per week. The outer surface of the wheel 43 is divided into seven major divisions or sectors 51, each marked successively "Sun.",

"Mon.", "Tue.", etc., corresponding to the successive days of the week. The major divisions or sectors 51 are subdivided into smaller equally spaced divisions 52 to represent fractional parts of each day, in the construction shown these minor subdivisions corresponding to six-hour intervals being provided with numeral indicia, although, if desired, the numeral indicia may be provided for smaller intervals.

This day of the week and hour indicia on the wheel 43 is adapted to be placed in registration with a stationary index pointer 53 carried by the fixed pivot standard 49, corresponding to the time when the device is 70 placed in operation. The gear rotates in the direction indicated by the arrow thereon, and at the leading edge of each day interval is a small threaded hole 55 for selectively receiving a switch tripping screw 56 (Fig. 6). The function of this screw is to render the apparatus inoperative to perform its switching operation on any particular day of the week. For example, if it is desired that the apparatus be made non-functioning on Sunday, the 80 screw 56 is inserted in the hole 55 at the leading edge of the Sunday sector. Said screw projects below the under side of the wheel 43 and is adapted to engage a switch tripping arm 57 disposed directly below the gear, as 90 shown in Fig. 6. Such arm is pivoted at 58 and is operatively connected with an insulating arm 59 from the outer end of which projects a switch element in the form of a contact pin 61. Normally, such pin engages between two spaced contact fingers 62 (Fig. 3) mounted on an insulating post 63 (Fig. 4) whereby the pin 61 completes a circuit between the fingers 62. A torsion spring 64 coiled about the pivot 58 normally tends to 100 retain the contact pin 61 in such position between the fingers 62. When the screw 56 is placed in the hole 55 of the Sunday interval, such screw will engage the arm 57 and separate the switch elements 61-62 at the appropriate time on Sunday to prevent operation of the main switch 22, remaining in contact with the arm 57, owing to the long slope or dwell thereof, a sufficient interval to prevent operation of the main switch notwithstanding 105 seasonal variations in its time of operation.

As will be later described, the switch elements 61-62, which I shall call the Sunday cut-out switch, are so connected with the relay switch 23 as to make the operation 110 of the latter non-effective when the switch elements 61-62 are separated. When the main switch 22 is to be operated every day of the week, the screw 56 is removed from the hole 55 in the Sunday interval of the gear wheel 115 43. To avoid the possibility of losing the screw, the latter may be inserted in a hole 55' located inwardly at a smaller radius of said wheel, at which point the screw will clear the tripping arm 57 without actuating the 120 130

same. If it is desired to make the apparatus non-functioning on two or more days of the week, the appropriate number of these screws 56 are inserted in the proper holes 55 corresponding to these day intervals.

Projecting from the reverse side of the gear wheel 43 are two diametrically opposite pins 65 which transmit an intermittent, step-by-step rotation to the toothed periphery of another large gear wheel 66 which is rotatably supported on the pivot standard 35 below the hour wheel 34, and also below the day of the week, or "Day" wheel 43. The driving ratio from the pins 65 on the wheel 43 to the teeth 67 on the wheel 66 is such that, for each rotation of the wheel 43, the wheel 66 will be advanced two tooth spaces, or the wheel 66 will make one complete revolution each year.

A detent 70 (Fig. 6) is normally urged into the teeth 67 by a spring 70' so as to hold the wheel 66 between its step-by-step advancements. The outer surface of such wheel is marked into twelve major divisions or sectors 68, each designated by the successive months of the year. Each month division is subdivided into smaller divisions 69 corresponding to weeks of the month, with numerals corresponding to weekly intervals associated therewith. The indicia 68—69 is adapted to be placed in appropriate registration with a stationary pointer index 71 corresponding to the time of the year when the device is placed in operation. Fixedly secured to the under side of the wheel 66, which I shall term the "month" wheel, is a cam 72 which effects a shifting of the switch actuating devices corresponding to seasonal variations of sunrise and sunset at different times of the year. Referring to Figs. 6 and 7, such cam cooperates with a shifter arm which is disposed below the month wheel 66 and which is pivotally mounted adjacent to one end on the pivot standard 49. Such arm, designated 73, has a cam riding point 74 which is continuously held in contact with the periphery of the cam under the action of a biasing spring 75 extending between a pin 76 on the arm 73 and a fixed pin, such as arbor 27, on the frame of the clock. The swinging end 73' of said arm is arranged to transmit shifting movement to an arm 78 which carries certain of the devices for actuating the relay or pilot switch 23. The arm 78 is pivotally mounted on the pivot stud 35 so that the switch actuating devices carried thereby swing concentrically of the path of movement of the tripping finger 37 revolving with the hour wheel 34.

Referring to Figs. 7 and 9, the pivot end 78 of the arm 78 may be provided with diametrically opposite slots 79 adapted to slip down over diametrically opposite pins projecting from the pivot stud 35 and arranged whereby, in the normal arc of movement of the arm 78, the slots 79 will be out of registry with such

pins so that the arm will be held against upward displacement along the pivot stud. The swinging end of said arm is formed with a raised shelf portion 78' upon which a wheel 82 is pivotally supported at 83, such wheel being disposed approximately in the plane of the hour wheel 34. Projecting from the outer side of said wheel or disk 82, in closely spaced relation, are two pins 84 and 85, the former of which is engaged by the tripping finger 37 in each revolution of the hour wheel 34. As said tripping finger engages this pin and rides past the same, the wheel or disk 82 is caused to oscillate about its pivot 83, thereby swinging the other pin 85 outwardly against the long curved arm 86, which actuates the relay switch 23, as will be presently described. Referring to Fig. 10, a wire spring 87 is secured to the under side of the shelf portion 78' and has its two ends extending outwardly to engage opposite sides of a pin 88 extending downwardly from the disc 82 whereby to automatically restore the disc to a predetermined normal position after each oscillation thereof by the tripping finger 37.

A pin 89 extends downwardly from the shelf portion and serves to center the two ends of the spring 87 so that the pin 88 will always be restored to a predetermined angular position. The edge of the shelf portion 78' may be formed with an arcuate notch 91 affording shoulders which positively limit the oscillatory movement of the pin 88. The end 73' of the shifting arm 73 extends into a slot 92 in the upwardly bent portion of the arm 78 so that swinging movement of the arm 73 will oscillate the arm 78 in a direction to advance or delay the time of engagement between the tripping finger 37 and pin 84. When the device is to be used in the north temperate zone of the earth's latitude, the shifting cam 72 will have its maximum radius approximately directly under the "Dec." division of the month wheel 66 so that when this point of the cam is bearing against the cam riding point 74 of the arm 73 the arm 78 supporting the switch actuating disc 82 will have been oscillated in a clockwise direction to approximately the position illustrated in Fig. 6. Hence, at this time of the year, when the days are shorter, the disc 82 will be advanced with respect to the direction of rotation of the tripping finger 37 so that the relay switch will be actuated earlier in the day. The low point of the cam 72 is approximately under the "June" division of the month wheel 66 and when this portion of the cam is in engagement with the cam riding point 74 the arm 73 will have swung inwardly towards the pivot axis 35, with consequent counterclockwise oscillation of the arm 78, to place the disc 82 in a location where the engagement of the tripping finger 37 with the pin 84 will be delayed until a later hour in each day.

The swinging of the two arms 73 and 78 in this direction is effected through the spring 75. In some instances it may be desired to definitely position the switch actuating disc 82 at one point so that the relay switch 23 will be operated at the same time each day instead of at varying times dependent upon sunset or sunrise. To provide for this mode of operation, the arm 73 has an extending portion 93 which is adapted to be engaged by a pin 94 on a swinging arm 95 (Fig. 6). The arm 95 is disposed below the day wheel 43 and is secured to a short pivot shaft 96. Secured to the outer end of said shaft is an actuating arm 97 disposed in convenient position for operation above the day wheel 43 (Fig. 3), and it will be evident that by oscillating the latter arm in a counterclockwise direction the pin 94 on the lower arm 95 oscillates the lever 73 in a direction to carry the cam riding point 74 outwardly to a position where it will not be influenced by the cam 72. The lever 73 is locked in such position by the pin 94 engaging a shoulder 98 at the end of the extending arm portion 93. As above remarked, at this time the switch actuating disc 82 will remain in a definite position so that the relay switch 23 will always be actuated at the same time each day.

The relay or pilot switch 23 comprises a switch blade 101 secured to a block of insulation 102 pivotally mounted on a pivot pin 103 extending between the clock frame and an angle bracket 104 secured to said frame. The swinging end of the blade 101 rides on the raised edge 105 of a metallic contact clip 106 secured to a block of insulation 107, the raised contact edge 105 having end stops for limiting the oscillation of the blade 101 (see Fig. 13).

In either extremity of its movement, the switch blade engages with terminal contacts 108 and 109 having suitable insulated mounting. A biasing spring 110 is pivotally connected between the insulating block 107 and a longitudinal pivot point on the switch blade 101 for completing the throw of the blade after the latter has passed beyond an intermediate position. The curved switch actuating arm 86 is fixedly connected with the insulated hub portion 102 of the switch blade, and, hence, swings about the pivot center 103, serving to throw the switch blade out of engagement with the contact 109 and into engagement with the contact 108 when said arm 86 is swung outwardly by the pin 85. Reverse movement of the switch blade back into engagement with the contact 109 is effected by the tripping finger 38 on the reverse side of the hour wheel 34 engaging with a dog 111 mounted on the hub portion 102 of the switch blade. Such dog is pivotally supported at 112 and has a weighted end normally tending to retain the dog in the operative position shown in Fig. 3. In the normal, counter-

clockwise rotation of the tripping finger 38, such finger will engage the nose of the dog and swing the switch blade into engagement with the terminal contact 109. If the hour wheel 34 should be revolved clockwise in the setting of the mechanism, the pivotal mounting of the dog permits the same to swing clear of the finger 38 as the latter moves back past the dog.

Referring now to the schematic circuit diagram of Fig. 2, it will be seen that current is supplied to the device through wires 115 and 116 which enter the housing 17 and are connected with the two main switch terminals 117, 118.

As previously remarked, the clock unit 20 may be manually wound or may be operated by an electric motor. In the preferred arrangement shown, such clock unit derives its operating energy from a small electric motor 119 which is connected to the main switch contacts 117, 118 through wires 121, 122. The mechanism 21, which actuates the main switch 22, also derives its power from a small electric motor 123, the circuit of which is controlled by the above described relay switch 23. A wire 124 leads from the switch terminal 117 and connects directly with one side of the motor 123. A wire 125 extends from the other switch terminal 118 and connects through the contact clip 106 with the relay switch blade 101. When said blade is in contact with the switch terminal 108 the circuit continues through wire 126 to one of the contacts of the Sunday cut-out switch 61, 62.

Assuming the contact pin 61 to be engaged in between the contact terminals 62, during weekday operation, the circuit will continue down through wire 127, in which a manually operated cut-out switch 128 is interposed, to a contact terminal 131 constituting part of a rotary switch associated with the motor driven switch actuating mechanism 21. The circuit is continued from the terminal 131 to a companion terminal 131' through a rotating contactor 132. Diametrically opposite to the terminals 131, 131' are two corresponding terminals 133, 133' which are adapted to be electrically connected when the contactor 132 revolves through a half revolution from the position shown. The two terminals 131' and 133' are cross connected by a wire 134, from which a wire 135 leads to the other terminal of the switch actuating motor 123.

Leading down from the other contact terminal 109 of the relay switch 23 is a wire 136 which connects with the contact terminal 133.

The switch actuating mechanism 21 may be of any desired construction appropriate for transmitting operating energy from the motor 123 to the main switch 22 for moving the latter between its closed and opened positions. In the preferred construction shown, the torque of the motor 123 is transmitted through

a speed reducing gear train generally indicated at 137 to one end of a heavy spiral spring indicated at 139. The energy stored in said spring is transmitted through gears to a rotary member 141 carrying a crank pin 142. A connecting rod 143 extends from this crank pin to the main switch 22. Automatically operating, half-revolution stop mechanism, generally indicated at 144, is associated with the spring 139 for covering the rotation of the crank element 141, such stop mechanism in and of itself forming no part of the present invention. When the main switch 22 is in the open position illustrated in Fig. 2, the revolving contactor 132 is engaging between the switch contacts 131, 131'. At sunset, or at a predetermined time interval earlier or later than sunset, the relay switch 23 swings over into engagement with its switch terminal 108 and completes the circuit to the switch actuating motor 123 down through wire 126 and switch contacting elements 131, 132 and 131'.

The motor 123 thereupon operates to transmit winding rotation to the spring 139. After the spring has been wound through a half-revolution, or other predetermined angular distance, the stop mechanism 144 is automatically tripped, whereupon the crank element 141, acting under the heavy tension of the spring, makes a quick rotation through a half revolution and effects a quick closing of the main switch 22 through the crank connecting member 143. The stop mechanism 144 stops the rotation of the crank element 141 at the end of this half revolution or one-cycle, with the main switch 22 held closed. Such rotation of the crank element 141 swings the rotary contactor 132 out from between the contacts 131, 131' and over into engagement between the opposite contacts 133, 133'. Hence, the motor circuit through relay switch contact 108 and wire 126 is broken, and the motor 123 immediately ceases operating. At sunrise, or at a predetermined hour in the morning, the relay switch 23 is swung back into engagement with its switch contact 109, thereby completing the motor circuit down through wire 136 and contacts 133, 133' to the motor 123. Thereupon, the motor again takes up operation, winding the spring 139, and finally tripping the stop mechanism 144 with the result that the crank element 141 is quickly revolved through a half revolution for opening the main switch 22. Such rotation of the crank element 141 swings the rotary contact 132 back into its former position between the switch contacts 131, 131', thereby breaking the circuit to the motor from the relay switch contact 109 and re-establishing the circuit from the other terminal 108, preparatory to the next actuation of the motor 123 at sunset.

It will be noted that in each step of the operation the relay switch 23 only operates to close the circuit of the motor 123, the opening of such circuit being effected by the

rotary contactor 132, and hence the relay switch is relieved of any arcing incident to the opening of such motor circuit. The closing of the main switch 22 connects the two power conductors 115, 116 with the main switch contacts 117', 118', from which conductors 146 extend to the electric sign or other device or apparatus to be controlled. If it is desired to have said main switch open the power circuit at sunset instead of closing the same, the crank pin 142 can be placed at a diametrically opposite point on the crank element 141, or the connection of the two conductors 126, 136 with the relay switch contacts 108, 109 can be reversed. The opening of the small manually operated switch 128 permits the relay switch 23 to be operated for testing or the like without causing operation of the main switch 22.

The foregoing description of the circuit diagram of Fig. 2 will explain the operation of opening and closing the main switch 22 when the relay switch 23 is swung to one side or the other under the control of the clock unit 20. Briefly summarizing the operation of this relay switch, it will be seen that the clock movement functions as a time controlled means for rotating the gear wheel 31 once every twelve hours which, in turn, revolves the hour wheel 34 once every twenty-four hours.

The hour wheel 34 functions as a rotating carrier for the two tripping members 37 and 38, which tripping members are angularly adjustable relatively to said carrier member for opening and closing the main switch 22 at different hours of the day. Once each revolution, the tripping member 37 is adapted to engage and operate the switch actuating member in the form of the pin 84 and its associated parts 82, 85 and 86, which transmit movement to the relay switch blade 101. The arm 78 constitutes a swinging supporting means operating to shift the switch actuating member 84 to different points of the path of movement of the tripping member 37 with seasonal variations of sunrise or sunset, i. e., for the short days of the year having an early sunset the switch actuating member 84 is shifted to a point in such path where its time of engagement by the tripping member 37 will occur earlier in the day, and, conversely, for the longer days when sunset occurs later the switch actuating member is shifted to a point in such path as to be engaged by said tripping member at a later time in the day. In this regard, the curvature of the motion transmitting arm or lever 86 is of particular importance for always transmitting substantially the same degree of angular throw to the switch blade 101 irrespective of the point to which the switch actuating member 84, 82 has been shifted.

That is to say, when said switch actuating member occupies the seasonal position illus-

trated in Fig. 3, it transmits motion to the lever 86 through a relatively long radius arm, whereas when such switch actuating member has been displaced to the other limit of its movement, corresponding to the long days of the year, it transmits motion to the lever 86 through a relatively short radius arm, viz., the radius arm extending from the pivot 103 to the point of engagement of the pin 85 with the lever 86. The normal position of such lever is illustrated in dotted lines in Fig. 3, and this normal position and the curvature of the inner edge of the lever are so proportioned and related to the shifting movement of the switch actuating member, that substantially the same degree of switch actuating movement will be imparted to said lever from the pin 85 irrespective of the point to which the switch actuating member has been shifted with seasonal variations. These characteristics of the lever 86 also increase the accuracy of the device by insuring in all seasonal positions of the switch actuating member the same time relation between the instant when the member 37 engages the member 84 and the instant when the switch blade 101 snaps over center. The full line illustration of said lever in Fig. 3 represents the position to which this lever is swung when the biasing spring 110 snaps the switch blade 101 over to the limit of its throw.

The manner in which the supporting member 78 is swung through cooperation between the seasonal cam 72 and follower lever 73 has been previously described. Similarly, the manner in which the relay switch can be made non-effective by the Sunday cut-out means 61, 62, through coaction of the screw 56 carried by the day wheel 43, has been previously described. If it should be desired to have the tripping member 37 engage the switch actuating member 84 at the same time each day, such is effected by swinging the arm 97 which, together with the arm 95 and pin 94, constitute holding means for swinging the cam following lever 73 and switch actuating member 84 to a position where they will not be influenced by the cam 72, and holding the same in such position.

When the device is to be placed in operation, the month wheel 66 is first angularly adjusted on the arbor 35 to have the proper month division and approximate day of the month register with the index member 71, corresponding to the month and day on which the device is placed in operation. The day wheel 43 is then angularly adjusted on its arbor 49 to place the appropriate day of the week and approximate hour of the day in registration with the index member 53 corresponding to the time when operation is to begin. After the two tripping members 37 and 38 have been properly adjusted on the hour wheel 34, the latter is placed on the arbor 35, and its numeral indicia 34' is

brought into matching registration with the corresponding numeral indicia 31' on the wheel 31.

These two wheels are then rotated together in mesh until the numeral indicia 29' on the wheel 29 appropriately registers with the index member 33 corresponding to the hour and approximate minute when the device is placed in operation. Thereupon, the gear 29 is moved back into mesh with the pinion 28, whereby it comes under the control of the time controlled means, and the pinion 42 is at the same time moved into mesh with the day wheel 43. The driving train from the time controlled means to the cam 72, which rotates once each year, is thereby completed, with the hour, day and month wheels in exact time relation corresponding to the time when the instrument first starts operating. If it is desired to close the main switch substantially at sunset, and if sunset occurs at six o'clock on that particular day, the tripping member 37 is angularly positioned in registry with the 6 p. m. numeral on the wheel 34. Thereafter, correction for earlier or later sunset with seasonal variation of sun time will occur automatically under the controlling action of the cam 72. If, at the above time when the instrument is set in operation, it is desired to actuate the relay switch at a predetermined time, say 15 minutes or a half hour, earlier or later than sunset, the tripping member 37 is angularly adjusted a corresponding distance to either side of the hour of sunset on that particular day.

Different cams 72, corresponding to different geographical locations or latitudes, may be mounted on the month wheel 66 for different points of installation of the instrument.

The shape of cam shown in Fig. 12 is intended for use in the north temperate zone, and it will be understood that by reversing such cam to place its high point under the June division of the month wheel, such cam can be employed in the south temperate zone.

In the above described embodiment, the main switch 22 is opened at the same time each morning, which time is predetermined by the angular setting of the tripping finger 38 relatively to the hour indications on the reverse side of the wheel 34. In Fig. 14 I have illustrated a modified embodiment wherein both switch movements correspond directly with sunset and sunrise. In such embodiment, there are two hour wheels 34a and 34b which are geared together, each rotating one complete revolution every 24 hours. Adjustably mounted on the outer side of each of such wheels is a tripping finger 37a and 37b adapted to engage, respectively, with switch actuating pins 84a and 84b on the discs 82a and 82b. The other pins 85a and 85b transmit movement respectively to the two curved arms 86a and 86b extending from opposite sides of the relay switch blade 101.

It will be understood from the foregoing that the engagement of the finger 37a with the pin 84a will transmit movement to oscillate the switch blade 101 over into engagement with the switch contact 109, and that engagement of the other tripping finger 37b with its companion pin 84b will oscillate the switch blade back in the opposite direction into contact with the other switch contact 108.

10 Disposed co-axially below the two hour wheels 34a and 34b are two month wheels 66a and 66b, each carrying a cam 72a, 72b. Such cams cooperate with shifting levers 73a and 73b which transmit shifting movement to the two arms carrying the discs 82a and 82b substantially as described of the preceding embodiment. The inner or adjacent ends of the two levers 73a and 73b are connected by a spring 75' which operates to retain the cam riding points of such levers in contact with their respective cams.

Rotation is transmitted to either of the two hour wheels 34a or 34b from suitable time controlled means through a gear train, such as has been previously described, whereby each wheel 34a, 34b revolves once every 24 hours. Rotating with one of said wheels, illustrated as the wheel 34a, is a pinion 148 which meshes with a relatively larger gear 149, driving the latter in a ratio to rotate once every two days. Such gear carries a pinion 151 which meshes with a wheel 43', driving the latter in a ratio to complete one revolution per week. Such wheel carries two pins 65' which transmit a step-by-step advancement, twice each week, to the month wheel 66b. The two month wheels 66b and 66a are geared together to rotate in synchronism. The two cams 72a and 72b carried by such wheels are appropriately shaped to advance and delay the actuation of the relay switch in accordance with seasonal variations of sunset and sunrise in the latitude in which the device is used.

45 If desired, the two shifting levers 73a and 73b may have the holding arms 97a and 97b associated therewith, whereby the shifting levers can be held in outwardly displaced positions for a fixed time of opening and closing the switch each day. The day-of-the-week wheel 43' may also be arranged to coact with a Sunday cut-out switch, as described of the preceding embodiment.

While I have disclosed what I regard to be the preferred embodiment or adaptation of my invention, nevertheless it will be understood that such embodiment is largely exemplary and that numerous changes and modifications may be made therein without departing from the essence of the invention. In most instances the switch 24 will be used as a relay switch for controlling the operation of a larger main switch, but it will be obvious that in some situations the so-called relay switch may, in fact, serve as the main

switch. Within its broader aspects, the invention is also adaptable to other than electrical uses, as for instance, instead of imparting movement to a switch such movement might be imparted to a valve element or any other device, the operation of which it is desired to control in predetermined relation to sunset or sunrise, or both.

I claim:—

1. In a time switch of the class described, the combination of time controlled means comprising a plurality of cooperating members adapted to engage in timed relation for effecting switching operations, automatic means for varying the time of engagement between certain said members with seasonal variations of sunrise, and automatic means for varying the time of engagement between certain others of said members with seasonal variations of sunset and independently of said first means.

2. In a time switch of the class described, the combination of time controlled means comprising a rotating member having cyclical timed movement and a second rotating member adapted to be engaged thereby for effecting a switching operation, and automatic means for varying the relative positions of the axis of rotation of said latter member with respect to the first and with seasonal variations of sunrise or sunset.

3. In a time switch of the class described, the combination of a time controlled member having movement in a cyclical path, a cooperating member adapted to be engaged thereby for effecting a switching operation, and automatic means for displacing said latter member to different points of the path of movement of said first member with seasonal variations of sunrise or sunset.

4. In a time switch of the class described, the combination of a time controlled member having movement in a cyclical path, a cooperating member adapted to be engaged thereby for effecting a switching operation, and automatic means comprising a rotating cam acting to vary the time of engagement between said two members in accordance with seasonal variations of sunrise or sunset.

5. In a time switch of the class described, the combination of a time controlled member having movement in a cyclical path, a cooperating member adapted to be engaged thereby for effecting a switching operation, a cam rotating approximately once each year, and means actuated by said cam for displacing said latter member to different points of the path of movement of said first member with seasonal variations of sunrise or sunset.

6. In an astronomical time switch, the combination of switch means, a switch actuating member, a tripping member having movement in a cyclical path and adapted to engage and operate said switch actuating member

once each day, time controlled means for governing the movement of said tripping member, a cam controlled by said time controlled means and completing approximately

5 one cycle of movement each year, and follower means responsive to said cam for displacing said switch actuating member to different points of the path of movement of said tripping member with seasonal variations of sunrise or sunset.

10 7. In an astronomical time switch, the combination of switch means, a switch actuating member, a rotating tripping member adapted to operate said switch actuating member once

15 each day, supporting means for said switch actuating member swinging substantially concentrically of the path of movement of said tripping member, time controlled means for governing the movement of said tripping

20 member, a cam controlled by said time controlled means and completing approximately one cycle of movement each year, and follower means responsive to said cam and connected with said supporting means for swinging

25 said switch actuating member to different points of the path of rotation of said tripping member with seasonal variations of sunrise or sunset.

8. In an astronomical time switch, the combination of switch means, a switch actuating member, a rotating carrier, time controlled means for effecting approximately one revolution of said carrier each day, a tripping member mounted on and adjustable to different

35 angular positions relatively to said carrier, said tripping member being adapted to actuate said switch actuating member, a cam controlled by said time controlled means and completing approximately one cycle of movement each year, and follower means responsive to said cam for displacing said switch actuating member to different points of the path of movement of said tripping member with seasonal variations of sunrise or sunset.

40 9. In an astronomical time switch, the combination of switch means, a switch actuating member, a rotating carrier, time controlled means for governing the rotation of said carrier, a tripping member mounted on

45 said rotating carrier and adjustable to different angular positions relatively thereto, said tripping member being adapted to engage said switch actuating member for moving said switch means to one position, means mounted on said rotating carrier for moving

50 said switch means to another position, a cam controlled by said time controlled means and completing approximately one cycle of movement each year, and follower means responsive to said cam for displacing said switch actuating member to different points of the path of movement of said tripping member with seasonal variations of sunrise or sunset.

55 10. In an astronomical time switch, the combination of switch means, a switch actuating member, a rotating carrier, time controlled means for governing the rotation of said carrier, a tripping member mounted on

60 said rotating carrier and adjustable to different angular positions relatively thereto, said tripping member being adapted to engage said switch actuating member for moving said switch means to one position, means mounted on said rotating carrier for moving

65 said switch means to another position, a cam controlled by said time controlled means and completing approximately one cycle of movement each year, and follower means responsive to said cam for displacing said switch actuating member to different points of the path of movement of said tripping member with seasonal variations of sunrise or sunset.

70 11. In an astronomical time switch, the combination of switch means, a switch actuating member, time controlled means, an hour wheel rotating under the control of said time controlled means, a tripping member moving with said hour wheel and capable of assuming different adjusted positions relatively thereto, said tripping member being adapted to engage said switch actuating member for operating said switch means, a month wheel rotating under the control of said time controlled means, a cam rotating with said month wheel, and means responsive to said cam for displacing said switch actuating member to different points of the path of movement of said tripping member with seasonal variations of sunrise or sunset.

75 12. In a time switch, the combination of switch means, a time controlled tripping member having movement in a cyclical path, a pivotally switching supporting member, a switch actuating member movably mounted thereon, means coacting with said supporting member for swinging said switch actuating member to different points of the path of movement of said tripping member with seasonal variations of sunrise or sunset, and an arm through which motion is transmitted from said switch actuating member to said switch means, said arm being curved and arranged with respect to said switch actuating member that the latter transmits substantially the same angular movement to said arm in each of the displaced positions of said switch actuating member relatively to the path of said tripping member.

80 13. In an astronomical time switch, the combination of switch means, a time controlled wheel, a tripping member rotating with said wheel, a supporting member arranged to swing substantially concentrically of said wheel, a disc pivotally mounted on said supporting member, a pin on said disc adapted to be engaged by said tripping member, cam means operatively connected to swing said supporting member to displace said pin to different points of the path of ro-

100

- tation of said tripping member with seasonal variations of sunrise or sunset, a second pin on said disc, and a curved arm operatively connected with said switch means and 5 adapted to be actuated by said second pin in the axial oscillation of said disc, said arm being curved and arranged in such relation that said second pin transmits substantially the same angular movement to said arm in 10 each of the displaced positions of said disc relatively to the path of rotation of said tripping member.
14. In a time switch, the combination of switch means, a switch rotatable actuating member, a time controlled member adapted to engage said switch actuating member to move said switch means to one position in predetermined time relation to sunset, cam means acting to shift the axis of rotation of 20 said rotatable member to thereby vary the time of engagement between said members in accordance with seasonal variations in the time of sunset, and means for moving said switch means to another position at a fixed 25 time period each day.
15. In a time switch, the combination of time controlled means comprising two co-operating members adapted to engage in timed relation for effecting a switching operation, automatic means for varying the time 30 of engagement between said members with seasonal variations of sunrise or sunset, and automatic means including a pivoted lever operated by one of said members for nullifying 35 said switching operation on a particular day of each week, such as Sunday.
16. In a time switch, the combination of a time controlled member having movement in a cyclical path, a cooperating member 40 adapted to be engaged thereby for effecting a switching operation, automatic means for displacing said latter member to different points of the path of movement of said first member in accordance with seasonal variations 45 of sunrise or sunset, and optionally actuatable means for holding said second member at a fixed point in the path of movement of said first member whereby said switching operation can be made to occur at a fixed time 50 each day.
17. In a time switch, the combination of switch means, a switch actuating member, a tripping member having movement in a cyclical path and adapted to engage and operate 55 said switch actuating member once each day, time controlled means for governing the movement of said tripping member, a cam controlled by said time controlled means, fol- 60 lower means responsive to said cam for displacing said switch actuating member to different points of the path of movement of said tripping member with seasonal variations of sunset, holding means adapted to be 65 optionally actuated for holding said switch 125 actuating member at a predetermined point in the path of movement of said tripping member for effecting the switching operation at a fixed time each day, and Sunday cut-out means controlled by said time controlled 70 means for rendering said switching operation non-effective on Sundays.
18. In a time switch, the combination of switch means, mechanism for moving said switch means to one position in predetermined time relation to sunset, and separate mechanism for moving said switch means to another position in predetermined time relation to sunrise, each of said mechanisms automatically varying the time of actuation of 75 said switch means independently of the other and in accordance with seasonal variations of sunset and sunrise.
19. In combination, an element to be actuated in predetermined time relation to sunset or sunrise, an actuating member operatively connected therewith, time controlled means, a tripping member governed thereby and having movement in a cyclical path for engaging said actuating member 80 and actuating said element, and cam means governed by said time controlled means, for moving said actuating member to different points of the path of movement of said tripping member with seasonal variations of 85 sunset or sunrise.
20. In an astronomical clock of the class described, a time controlled wheel geared to make one revolution a day, a trip lever carried by said wheel and adjustable thereon to set it at any hour of the day, a switch mechanism, means operated by said trip mechanism to control said switch at the prescribed hour of the day, a second wheel 100 geared to the first to make one revolution a day, a trip mechanism adjustably mounted on said second wheel, and means engaged by said second trip mechanism for operating said switch.
21. In an astronomical clock of the class 110 described, a time controlled wheel geared to make one revolution a day, a trip lever carried by said wheel and adjustable thereon to set it at any hour of the day, a switch mechanism means operated by said trip mechanism to control said switch at the prescribed hour of the day, a cam geared to said wheel and operated thereby through one revolution a year, a lever engaging said cam and operated thereby to shift the switch operating means to thereby alter the time of its engagement by said trip mechanism, a second wheel geared to the first to make one revolution a day, a trip mechanism adjustably mounted on said second wheel, and means engaged by said second trip mechanism for operating said switch, a cam geared to said second wheel and operated thereby through one revolution a year, a lever en- 115 120 125 130

gaged by said second cam and operated thereby to alter the time of engagement of said second trip mechanism with said second switch operating means.

5 In witness whereof, I hereunto subscribe my name this 27th day of February, 1929.

CHARLES E. DE LONG.
